UNITED STATES PATENT OFFICE

96,303

DESIGN FOR A BAG

Charles B. Elmore, Fairfield, Conn.

Application May 9, 1935, Serial No. 56,760

Term of patent 7 years

To all whom it may concern:

Be it known that I, Charles B. Elmore, a citizen of the United States, residing at Fairfield, in the county of Fairfield and State of Connecticut, have invented a new, original, and ornamental Design for a Bag, of which the following is a specification, reference being had to the accompanying drawing, forming part thereof.

Fig. 1 is a perspective view of a bag, supported in upright position, showing my new design.

Fig. 2 is an edge view of the bag, positioned as shown in Fig. 1.

Fig. 3 is a plan view of the bag lying flat.

Fig. 4 is an edge view of the bag lying flat. In the drawing, the dotted lines represent stitching.

I claim:

The ornamental design for a bag as shown and described.

CHARLES B. ELMORE.
